164,904

PORTABLE POWER-OPERATED SANDING MACHINE

Arthur N. Emmons, Nedrow, N. Y., assignor to
Porter-Cable Machine Company, Syracuse,
N. Y., a corporation of New York

Application February 24, 1951, Serial No. 14,315

Term of patent 14 years

(Cl. D37—1)

To all whom it may concern:

Be it known that I, Arthur N. Emmons, a citizen of the United States, residing at Nedrow, county of Onondaga, State of New York, have invented a new, original, and ornamental Design for a Portable Power-Operated Sanding machine, of which the following is a specification, reference being had to the accompanying drawing, forming part hereof.

Fig. 1 is a top plan view of a portable power operated sanding machine, showing my new design.

Fig. 2 is a side elevational view, while;

Fig. 3 is a side elevational view of the other side thereof.

Fig. 4 is an end elevational view looking to the right, Fig. 1.

Fig. 5 is a front elevational view looking to the left, Fig. 1.

I claim:

The ornamental design for a portable power-operated sanding machine, as shown.

ARTHUR N. EMMONS.
